SPRAYING ATTACHMENT

Filed June 23, 1928

Inventor:
Eugene F. Martinet

Attorney.

UNITED STATES PATENT OFFICE

EUGENE F. MARTINET, OF CLEVELAND, OHIO, ASSIGNOR TO THE P. A. GEIER COMPANY,
OF CLEVELAND, OHIO, A CORPORATION OF OHIO

SPRAYING ATTACHMENT

Application filed June 23, 1928. Serial No. 287,840.

My invention relates to improvements in spraying attachments, and more particularly to such attachments as are adapted primarily for use in connection with low-pressure air-moving apparatus, such as suction cleaners, although not essentially restricted to such use. The objects of my invention are the provision of essentially simple means, and the rearrangement of parts for insuring a cheap, adaptable and efficient appliance of this general character, and one not liable to get out of order.

Suction cleaners when operating at normal speed provide an excess of output for the average spraying conditions, but the pressure of the air from the outlet is relatively low, so that it is desirable not only to employ the partial vacuum produced by a controlled outflow for spraying the desired liquid or powder used, but air pressure preferably is simultaneously applied interiorly of the container. This pressure must be instantly relieved when the spraying operation ceases, in order to prevent any overflow from the liquid tube, and consequent waste.

Accordingly, I have devised a spraying attachment in association with the liquid container, which permits the escape of air without applying pressure to the container or affecting the contents by producing any appreciable vacuum at the tip of the liquid tube. These simple means, shown in two modified forms, however, automatically direct a concentrated air current over the tip of the liquid tube and apply pressure interiorly of the container at the same time, when spraying operations are begun. Conversely, the air is permitted to escape and the pressure is released automatically, interiorly of the container, when the operator releases the attachment from normal use.

Furthermore, when applying certain classes of sprayed materials, it is desirable to direct a drying current of air over the sprayed surface, or to use such air currents for spreading or for dissipating powdered materials. These requirements also have been kept in mind and adequately met by my improvement, the features of which may be explained

in connection with the accompanying drawings, wherein:

Figure 1 is a view in elevation of a low-pressure spraying attachment incorporating my improvements,

Fig. 2 is a fragmentary view thereof on a larger scale and in vertical section,

Fig. 3 is a front view on the same scale,

Fig. 4 is a fragmentary vertical section of a modified form of attachment, and

Fig. 5 is a front view of the device of Fig. 4.

Throughout the several figures of the drawings, I have employed the same character of reference to indicate similar parts.

The liquid container, Fig. 1, preferably comprises a glass jar *a*, which permits the contents to be seen. Its top is screw-threaded to accommodate the screw cap *a'* which mounts the composite handle member and air chamber, terminated by the controlling means, later described in detail, and the liquid tube *a''* extending nearly to the bottom of the jar.

Referring to the enlarged showing of the cap and parts mounted thereon, Figs. 2 and 3, it will be seen that the lower portion of the air chamber *b* is open so that the air from a connected vacuum cleaner hose (not shown) may readily escape around the sides of the liquid tube without affecting the contents of the liquid container. A tubular member *c*, upwardly terminating in flanged relation above the composite control member *d*, slidably extends diametrically through the air chamber to communicate with the liquid container *a*.

These members are acted upon by a compression spring *g* normally holding the tube *c* in its extended position of Fig. 2 with the lug *c'* bearing against the inside edge of the opening in cap *a'*. It will be noted that in this position the elongated slot *c''* in tube *c* is maintained exteriorly of, and above the upper wall of the air chamber *b*.

When, however, member *d* and tube *c* are depressed by the thumb of the user, assuming that air is being supplied to air chamber *b*, it will be seen that shortly after the nozzle opening *d'* is brought into register with the tip of tube *a''*, the slot *c''* is brought into register with the interior of the air chamber proportion-

tionately with the depression of the tube. As the flanged upper opening is closed by the user's thumb, a proportionate amount of air will enter the liquid chamber, thereby producing a pressure which will assist the partial vacuum initially produced at the tip of liquid tube a'' for elevating and spraying the contents of the jar. An opening d'' in the rectangular extension d^3 of composite member d , registers with the liquid tube and permits the member d to be depressed until the extension d^3 abuts the top of the screw cap a' , whereby the maximum spraying effect is obtained.

15 Accordingly, the user is able to obtain readily controlled and variable spraying effects merely by regulating the depression of members c and d , with the corresponding variation in the positions of slot c'' and nozzle d' , which is narrowed in its upper portion, as will be observed by the showing in Fig. 3.

In the completely depressed position, slot c'' is fully entered within the air chamber, thereby introducing maximum air pressure to the closed jar a , while the partial elevation of tube c will correspondingly withdraw the slotted opening from the air chamber, and immediately the slot rises above said air chamber, normal air pressure is restored within the jar, since the slot serves then as a vent. Moreover, if the user suddenly finds it necessary to discontinue spraying operations, he instantly removes his thumb from its closed position of tube c , whereupon the air pressure is even more promptly released from the jar and spraying operations automatically are checked, with no waste of liquid from the jar.

The spraying attachment shown in Figs. 4 and 5 is of modified type, in that the cylinder e , having respectively, inlet and vent openings, e' , e'' , is rotatable as the control member d is depressed, by means of the spiral stem f , which passes through a slot f' in the upper wall of air chamber b . The depression of member d and e , as before, serves to cut off the vent opening e'' , meanwhile turning the inlet opening e' through a variable arc, up to approximately 120° , so that more and more of the air is trapped, and an increasing pressure is applied to the contents of the liquid container during the registration of nozzle member d^4 with the tip of tube a'' . Relaxing pressure of the thumb upon member d causes the spring g reversely to rotate stem f and cylinder e , thereby turning the inlet e' to its inert or forward position, and venting the air laterally through e'' , when the position of Fig. 4 is reached.

60 It will be seen that the same general purposes and results are attainable with both modifications of my improvement, since the nozzle is brought into operative relation with the tip of the liquid tube concurrently with the actuation of the duct member of each for

closing the external air vent and then trapping the air variably in the air pressure chamber to produce an operating pressure within the closed liquid container. The sliding closure member of each is positioned by the rectangularly extending perforated portion embracing the liquid tube, normally with a shielding section deflecting the air away from the tip of said tube, so that the air currents may escape and be made useful for drying purposes, and the like.

With the nozzle having a substantially pear-shaped opening, the air currents may be variably focused over and about the tip of the liquid tube in order to produce different spraying effects, depending upon the depression of the controlling member, which involves no further regulating or valve mechanism for controlling the flow of air.

Both appliances are simple and cheap to construct and they automatically apply and relieve the air pressure within the liquid container, alternatively to augment the liquid supply or to prevent its waste. I may say that while employing the expressions, "liquid container" or "liquid tube" descriptively herein, and in the claims, it should be understood that my improvements are not thereby restricted, and are intended to include the spraying of any suitable liquids, powders, and the like.

Having now described and shown modified embodiments of my improvement, I hereby claim and desire to secure by Letters Patent, the following:

1. In a spraying attachment, the combination with a liquid container and its protruding liquid tube, of an air chamber forwardly open adjacent to the tube, and a control member slidably positioned between the open end and said tube having a shielding portion for the tip of the latter and a vertically graduated opening adapted to be brought into register therewith, substantially as set forth.

2. In a spraying attachment, the combination with a liquid container and its protruding liquid tube, of an air chamber forwardly open adjacent to the tube, and a sliding closure member therefor, comprising a shielding portion for the tip of said tube, a positioning member embracing the tube, and a nozzle member adapted to be brought into register therewith, substantially as set forth.

3. In a spraying attachment, the combination with a liquid container and its protruding liquid tube, of an air chamber, a nozzle member therefor having a discharge opening of graduated size adapted to be variably brought into register with the tip of the liquid tube, and means for effecting the relative movement of said nozzle member with respect to the tip of the liquid tube, whereby variable spraying effects are obtained, substantially as set forth.

4. In a spraying attachment, the combination with a liquid container and its protruding liquid tube, of an associated air chamber forwardly open adjacent to the tube, a sliding closure member therefor, comprising a shielding portion for the tip of said tube and a nozzle member adapted alternatively to be brought into register therewith, a sliding duct member extending from the air chamber into the liquid container normally open to the external air and having a slotted opening, and a thumb piece connecting the latter and said closure member, whereby the external air opening temporarily is closed upon concurrently actuating the connected parts, substantially as set forth.

In testimony whereof I do now affix my signature.

EUGENE F. MARTINET.
